US0D1022369S

(12) **United States Design Patent** (10) Patent No.: **US D1,022,369 S**
(45) Date of Patent: ** Apr. 9, 2024

(54) **ICE SCRAPER**

(71) Applicant: **GARANT GP**,
Saint-François-de-la-Rivière-du-Sud
(CA)

(72) Inventors: **Carl Blouin**, Lévis (CA); **David Boies**,
Lévis (CA); **Hugo Lepage**, Rimouski
(CA)

(73) Assignee: **GARANT GP**,
Saint-François-de-la-Rivière-du-Sud
(CA)

(**) Term: **15 Years**

(21) Appl. No.: **29/867,932**

(22) Filed: **Nov. 14, 2022**

(51) LOC (14) Cl. **07-05**

(52) U.S. Cl.

USPC **D32/46**

(58) **Field of Classification Search**

(57) **CLAIM**

The ornamental design for an ice scraper, as shown and described.

DESCRIPTION

FIG. 1 is a perspective front view of an ice scraper showing our new design;

FIG. 2 is a front view of the ice scraper of FIG. 1;

FIG. 3 is a rear view of the ice scraper of FIG. 1;

FIG. 4 is a first side view of the ice scraper of FIG. 1;

FIG. 5 is a second side view of the ice scraper of FIG. 1;

FIG. 6 is a top view of the ice scraper of FIG. 1; and,

FIG. 7 is a bottom view of the ice scraper of FIG. 1.

The broken lines shown in the FIGS. 1-7 form no part of the claimed design.

1 Claim, 5 Drawing Sheets
